United States Patent Office.

ALBERT BETTELEY, OF BOSTON, MASSACHUSETTS.

Letters Patent No. 96,870, dated November 16, 1869.

IMPROVED WOOD PAVEMENT.

The Schedule referred to in these Letters Patent and making part of the same.

To all whom it may concern:

Be it known that I, ALBERT BETTELEY, of Boston, in the county of Suffolk, and State of Massachusetts, have invented certain new and useful Improvements in Wooden Pavements; and I do hereby declare that the following, taken in connection with the drawings which accompany and form part of this specification, is a description of my invention, sufficient to enable those skilled in the art to practise it.

Pavements of wood are usually composed of prismatic blocks, having the end of the grain or fibre of the wood presented to the road-bed and to the travel on the pavement. Such blocks are usually cut from large and consequently valuable timber, this adding materially to the cost of the pavement.

My improved pavement is made up of cylinders or cylindroids of wood, of small diameters, such as can be formed from young trees or saplings, of, say, from about four to seven inches diameter, of which a great quantity can be culled out from trees of larger growth, to the positive benefit of the latter. Savin trees and cedars may also be utilized in my pavement, as being commonly trees of small growth, which are to be found in great abundance, and are very durable, as being less liable to decay than pine, spruce, and hemlock, or other woods of which wooden pavements are commonly made.

But my invention does not consist, broadly, in a pavement made of blocks in the form of wooden cylinders placed with the grain or fibre in a vertical direction, as such pavements have before been made.

My invention consists in a pavement made up of wooden cylinders or cylindroids, cut with their ends parallel and inclined in the same direction to the axis of the cylinders, so that the grain of the wood shall be inclined to the road-bed and to the travel on the pavement, and in scoring the cylindroids, or the blocks described, preferably on but one side of each block, though

they may be scored on opposite sides, so that when the rows of blocks are alternately inclined in opposite directions, the blocks of one row interlock with the blocks of the rows adjoining on either side, and thus one block supports its neighbors, and is prevented from vertical displacement, and also prevents vertical displacement of the adjoining interlocked blocks.

Figure 1, of the drawings, shows in side elevation two rows of blocks in a pavement embodying my invention, the row nearest the eye being shown in full lines, and the row beyond, in the rear, partly in dotted lines;

Figure 2, shows an end view of four rows of a pavement embodying my invention; and

Figure 3 shows in plan a portion of my improved pavement.

Figs. 2 and 3 showing the blocks as interlocked by reason of being scored on one side.

It will be obvious that within certain limits, the deeper the scoring on the side or the sides of each block, the closer the rows of blocks will be brought together in one direction; and the smaller will be the interstices left between them, and the greater will be the area of actual wood in the pavement, and the smaller will be the amount of cement or sand or gravel-filling between the pavement-blocks.

The acute-angular edge of the upper end of each block may be removed, if desired, to afford additional holding-scores or depressions for the feet of horses.

I claim a wood pavement, composed of cylinders or cylindroids, the adjacent rows of which are scored on one or both sides, and are interlocked and inclined in opposite directions.

ALBERT BETTELEY.
